UNITED STATES PATENT OFFICE.

GEORGE SHAKESPEARE WILKINSON, OF LONDON, ENGLAND, ASSIGNOR TO THE
AIRCRAFT MANUFACTURING COMPANY, LIMITED, OF LONDON, ENGLAND.

MEANS FOR STARTING THE ENGINES OF AEROPLANES.

1,331,791.

Specification of Letters Patent. Patented Feb. 24, 1920.

Application filed September 9, 1919. Serial No. 322,741.

To all whom it may concern:

Be it known that I, GEORGE SHAKESPEARE WILKINSON, a subject of the King of Great Britain, residing at London, England, have invented new and useful Improvements in Means for Starting the Engines of Aeroplanes, of which the following is a specification.

This invention relates to apparatus for enabling the power derived from the engine of an automobile vehicle to be utilized for starting the engine of an aeroplane by "swinging" the propeller, as described in the specification accompanying a previous application for Letters Patent, Patent No. 1,313,693, of August 19, 1919; the primary object of the present invention being to provide means for enabling such apparatus to be employed for starting the engines of aeroplanes wherein the axis of the propeller stands at a considerably greater height above the ground, or makes a greater angle with the horizontal, than has heretofore been usual.

In the arrangement described and illustrated in the specification above referred to, the substantially horizontal telescopic starter-shaft, which is carried by the automobile and provided at its outer end with a clutch-member adapted for engagement with and automatic disengagement from a clutch-member fixed concentrically on the propeller-hub, is coupled by a universal joint to a short horizontal shaft journaled in a bearing which is carried by a pillar on the chassis of the automobile, the level of this bearing corresponding, approximately, to the usual level of the propeller-hub of an aeroplane when the latter is standing upon the ground. Hence the telescopic starter-shaft, although angularly adjustable about its point of connection with the short horizontal shaft on the automobile, cannot advantageously be used to start an engine the propeller hub of which stands at a level differing widely from that of the bearing upon the pillar of the automobile; it being obvious that the best results are obtainable only when the axes of the propeller and of the telescopic starter-shaft extend in approximate alinement with one another, while any great elongation of the starter-shaft, with a view to counteracting the effect

of considerable disparity in level between said bearing and the propeller-hub, would in practice be found inconvenient. 55

According to the present invention, the level of the bearing carried by the pillar of the automobile is made adjustable so that this bearing, although capable of normally standing at a level to suit the propellers of aeroplanes of the dimensions hitherto commonly met with, can be raised at will to a height corresponding to that of the propeller-hub of the much larger aircraft now coming into use for certain purposes. In addition, means may be provided for facilitating the manipulation of the starter-shaft, more especially when raised beyond convenient reach from the ground, 60 and also for holding the telescopic starter-shaft steady when engaged with the clutch-member on a propeller-hub standing at any height above the ground within the range of adjustment of the bearing carried by the 65 pillar of the automobile.

The bearing for the short horizontal shaft may either be adjustable in the vertical direction upon the pillar, or this pillar itself may be made telescopic; while driving connection between the short horizontal shaft and the engine-shaft of the automobile may be maintained by means of an upright shaft which may be telescopic and which, if the pillar be also telescopic, is journaled in 80 bearings upon the upper or movable and the lower or stationary portions of the pillar, bevel gearing being interposed on the one hand between the short horizontal shaft and the upper part of the upright shaft 85 and on the other hand between the lower end of the upright shaft and a dog-clutch member which, when the starter is not in use, may run freely upon the engine-shaft or upon a shaft driven thereby. Any convenient means, such for example as screw-gear, or rack-and-pinion mechanism provided with a locking-device, may be employed for adjusting the level of the bearing for the short horizontal shaft or the effective 90 height of the pillar. 95

In the accompanying drawings, Figure 1 is a side elevation (partly in section) of the front portion of an automobile provided with one form of the improved apparatus 105 of the present invention, wherein the pillar

is telescopic and incloses an upright telescopic shaft; while Fig. 2 is a rear elevation of the same, the lower section of the pillar being shown in section toward the 5 left hand side of its center line. Figs. 3, 4 and 5 illustrate portions of the apparatus in greater detail, each in sectional side elevation and to a larger scale than Figs. 1 and 2. Fig. 3 shows the junction between 10 the upper end of the stationary portion and the lower end of the slidable portion of the telescopic pillar, and between the corresponding sections of the upright telescopic shaft; Fig. 4 shows the junction between the 15 short horizontal shaft and the starter-shaft, and between the former shaft and the upper section of the upright telescopic shaft, respectively; and Fig. 5 shows the outer end of the starter-shaft. Fig. 6 shows the 20 tail of a clamping device for the struts which adjustably support the overhanging end of the starter-shaft.

Upon the chassis 11 of the automobile is mounted an upright hollow telescopic pillar 25 comprising two sections whereof the lower section 12 is fixed to the chassis while the upper section 13, which is cylindrical throughout the greater part of its height, is slidably vertically within the lower section 30 through guide-bearings 14 and 15 at the upper and lower ends of the latter and through intermediate bearings 16 and 17; the several bearings being spaced apart at such distances that the upper section 13 of the 35 pillar is never held by less than two bearings and is consequently kept steady even when fully extended. Fixed to the rear side of the upper section 13 is an upright rack 18 which constantly meshes with a spur pinion 19 40 fast on a transverse horizontal shaft 20 which is journaled in bearings near the upper end of the lower section 12 of the pillar; the shaft 20 also carrying a bevel wheel 21 (indicated by dotted lines in Fig. 45 3) which meshes with a bevel pinion 22 on the inner end of a short horizontal shaft 23 journaled in a bearing 24 on the lower section 12. On the outer or rear end of the shaft 23 is fixed a hub 25 carrying a series 50 of radial arms 26 by means of which the shaft can be rotated by hand to raise or lower the upper section 13 of the pillar; the rotation of the shaft 23 being normally prevented by the engagement, between adjacent 55 teeth of a series 27 on the hub 25, of a stoppin 28 inserted removably in a hole in the adjacent end of the bearing 24. The rack 18 slides through a groove in each of the bearings 14, 15, 16 through which it passes, and 60 thus constitutes a feather-key to prevent rotation of the upper section 13 relatively to the lower section 12 of the pillar. The lower bearing 17 presents a footstep to receive the weight of the upper section 13 of the pillar 65 when in its lowest position; while a spring-

pressed locking-pin, indicated at 16^a (Fig. 2) carried by the lower section 12 and adapted to engage in one or other of a vertical series of holes in the upper section 13, serves to support the latter at intermediate levels. 70

Immediately beneath the base of the lower section 12 of the telescopic pillar is mounted a gear-box 29, serving as the gear-box of the automobile and containing mechanism for transmitting motion from the engine-shaft 75 30, at variable speed and in either direction at will, under manual control, to the driving road-wheels by way of the usual Cardan shaft 31, or to the starter-shaft, alternatively as may be required. This may be accomplished by well-known gear connections together with a clutch mechanism, substantially like that shown and described in the Hucks Patent, No. 1,313,693, of August 19, 1919, but as the construction and internal 80 arrangement of the gear-box 29 forms no part of the present invention, it need not be further alluded to in this description.

From within the gear-box 29 rises, coaxially with the telescopic pillar, an upright telescopic rotary shaft which extends through both sections 12 and 13 of the pillar and serves to transmit motion from the driving mechanism within the gear-box to the starter-shaft. The upright shaft comprises 90 two sections whereof the lower section 32, which is in driving connection with the necessary motion-transmitting mechanism in the gear-box and is journaled in and supported by a suitable bearing 32^a in the latter, passes through a sliding bearing 33 mounted within the lower portion of the upper section 13 of the pillar. The lower section 32 of the telescopic shaft is of square section and passes through a correspondingly squared 95 socket 34 fixed within the lower end of the tubular upper section 35 of the shaft, while this latter section 35 is journaled in and depends from a bearing 36 at the upper end of the upper section 13 of the pillar and is 100 steadied by a bearing 37 mounted within the section 13 of the pillar above the sliding bearing 33 therein; so that, as the upper section 13 of the pillar descends, the lower section 32 of the shaft is received within the 105 tubular upper section 35 of the same without interruption to the driving connection 110 between them.

Fast on the upper end of the upper section 35 of the telescopic shaft is a bevel pinion 38 in mesh with a bevel wheel 39 which is fast on a short horizontal shaft 40 journaled in bearings in a hood 41 forming a cap for the upper section 13 of the telescopic pillar; the short shaft 40, which extends fore-and-aft of the automobile, being connected by means of a universal joint 42 to the inner or rear end of the main section 43 of the starter-shaft, which latter is itself extensible, as hereinafter explained. The 115 120 125 130

overhanging weight of the starter-shaft is partially sustained by a sway-beam 44 fulcrumed at a transverse horizontal axis 45 in a bifurcated bracket 46 carried by an up-right pintle 47 which is rotatable in a bearing at the top of the hood 41; the front end of the sway-beam 44 being coupled by a link 48 to a thimble 49 forming a journal for the starter-shaft section 43 between a pair of collars 50, 50 fixed thereon near the middle of its length, while the rear end of the sway-beam is anchored by an elastic connection, consisting of strong elastic cords 51, to points 52 at the lower ends of a pair of skirt-like brackets 53 which depend from beneath the hood 41 at its opposite sides in such manner as to clear the upper end of the lower section 12 of the telescopic pillar when the upper section 13 of the latter occupies its lowest position. The arrangement is such that, although the upper section 13 of the pillar is incapable of rotation relatively to the lower section 12, the starter-shaft can be swung through a moderately wide horizontal angle about the universal joint 42; the pintle 47 and elastic cords 51 permitting a corresponding horizontal angular movement of the sway-beam 44.

The starter-shaft comprises, in addition to the main section 43 (which is formed as a cylindrical tube) a telescopic extension 54, of square section, which is slideable through a correspondingly-squared socket 55 at the front or outer end of the main section 43; the rear end of the shaft-extension 54 having a flange 56 by which it is guided in its movements lengthwise of the main section, while a strong elastic cord 57, stretched between points of attachment 58 and 59 at the rear ends of the extension 54 and main section 43 respectively, constantly tends to retain the extension retracted within the main section as in Fig. 5. The retraction of the shaft-extension 54 is limited by a padded shoulder 60, near its outer end, encountering the outer extremity of the main section 43.

The outer end of the shaft-extension 54 has a pair of oppositely-directed radial studs 61, 61 upon which a gimbal-ring 62 is pivotally supported, this gimbal-ring being provided with a pair of oppositely-directed radial pins 63 adapted to engage detachably a pair of undercut notches in the wall of an open cylindrical fitting (not shown) fixed concentrically on the hub of the aeroplane propeller, substantially as set forth in the specification already referred to. The pins 63 may, as indicated in Fig. 2, be lengthened so as to constitute handles for facilitating the adjustment of the starter-shaft in the required position. When this has been effected, and the shaft-extension 54 is ready to be drawn out so as to permit of the pins 63 engaging the fitting on the hub of the aeroplane propeller, the outer end of the

main section 43 is steadied by means of an adjustable support hereinafter described.

Fig. 1 shows, in full lines, the telescopic pillar extended to its maximum height, and the starter-shaft occupying a horizontal position; the upper limit of the range of permissible angular adjustability of the starter-shaft and sway-beam in a vertical plane being indicated in dotted lines. The same figure shows, in dotted lines, the starter-shaft when the telescopic pillar is contracted to its minimum height; the starter shaft and sway-beam being shown both as occupying a horizontal position and also as angularly depressed to the lower limit of their range of permissible angular adjustability in a vertical plane. Fig. 2 shows, in full lines, the telescopic pillar reduced to its minimum height, and in dotted lines, the pillar extended to its maximum height.

In order to enable the outer end of the starter-shaft 43, 54 to be readily manipulated by the attendant when the telescopic pillar is extended so as to raise the starter-shaft beyond convenient reach of the ground, a vertically-adjustable staging is provided at the front end of the automobile; this staging comprising a braced rectangular framework 64 of metal tubing which extends in a fore and aft vertical plane and which is supported by and slideable vertically upon an upright post 65 fixed by its lower end to one side member of the chassis and stayed from its upper end to the other side member of the chassis and to the upper end of the lower section 12 of the telescopic pillar by means of tubular braces 66 and 67 respectively. The framework 64 is attached to the upper and lower ends of a sleeve 68 fitted to slide vertically upon the post 65; the sleeve carrying a spur pinion (not shown) which engages a vertical rack 69 fixed to the post and is adapted to be rotated by means of radial arms 70 carried by a short shaft whereon the pinion is fast, so that, by moving the arms 70 by hand, the sleeve 68 and framework 64 can be raised or lowered as required. Means (not shown) comprising a locking-pin (similar to 28) adapted to engage between teeth (similar to 27) on the hub which carries the arms 70, may be employed to lock the sleeve and framework at any desired level. The rack 69 also constitutes in effect a feather-key for preventing rotation of the sleeve 68 about the post 65, which is cylindrical. The framework 64 carries, at different levels, two platforms 71 and 72 which are respectively hinged to brackets on upper and lower cross-members 71^a and 72^a of the framework, so as to be capable of being swung into their horizontal operative positions as required; the outer ends respectively of the upper and lower platforms, when in operative position as shown in Figs. 1 and 2, being supported by hinged struts or ties 71^b 130

and 72^b; while these struts or ties are adapted to be disconnected so as to permit of either platform being folded against the framework 64 when not in use.

5 The adjustable support, by means of which the outer end of the main section 43 of the starter-shaft is steadied after being adjusted in readiness to engage the propeller-hub, comprises a pair of tubular struts 73, 74 which cross one another in a transverse direction X-wise beneath the shaft 43 so as to permit of a bearing for the latter resting in the V-crutch thus formed; the angular relation of the struts to one another, which is 10 adjustable in accordance with the angular adjustment of the starter-shaft in both a vertical and a horizontal direction, being maintained by a clamping-device which also serves to retain the shaft in position within 15 the crutch.

20 For this purpose the lower ends of the struts 73, 74 rest, by means of ball-and-socket joints 75, 76, on brackets 77 at the outer corners of whichever platform 71 or 72 is 25 for the time being in its horizontal operative position, each socket 75 or 76 being secured to the bracket by means of a clamping-screw 78 (Fig. 1); while the struts, at the point where they cross one another below the shaft 30 43, are held each between a pair of notched clamping-plates 79 or 80 (Fig. 6) which are threaded over a substantially horizontal bolt 35 81. On the threaded end of the bolt are screwed a pair of lock-nuts 81^a, while to the 40 opposite end a spanner-handle 82 is hinged, and between this handle and the nearest of the clamping plates the bolt 81 passes through a thimble 83 to which is hinged a short upright prop 84 carrying at its upper 45 end a bearing 85 which embraces a journal provided on the shaft 43 between a pair of collars 86, 87 thereon. When, the bolt 81 having been loosened, the starter-shaft is 50 being adjusted in operative position, the bolt 81 itself and clamping-plates 79, 80 will follow the movements of the shaft and cause the struts 73, 74 to assume a corresponding mutual angular relation; whereupon the bolt 81 is tightened so as, by drawing the clamping-plates together to hold the struts rigidly 55 in the position to which they have been brought.

55 In some cases the bearing for the short horizontal shaft, or the entire pillar, together with the starter-shaft and attached parts, may be so mounted as to be rotatable about the axis of the upright shaft; such an arrangement, which would permit of the starter-shaft extending in any desired direction 60 relatively to the automobile, being convenient where, for example, the engines of a number of aeroplanes drawn up in order upon an aerodrome require to be started in rapid succession.

65 Having now particularly described and

ascertained the nature of my said invention, and in what manner the same is to be performed, I declare that what I claim is:—

1. In an apparatus for utilizing the power of the engine of an automobile for starting 70 the engine of an aeroplane by swinging the propeller, the combination of an upright pillar, mounted upon the automobile, a short horizontal shaft supported in a bearing at the upper end of said pillar, said shaft being adapted to be driven from the engine of the automobile, a universally jointed shaft, connected with said horizontal shaft, and adapted to be coupled with the propeller of the aeroplane, and means for adjustably extending 75 said supporting pillar.

2. In an apparatus for utilizing the power of the engine of an automobile for starting the engine of an aeroplane by swinging the propeller, the combination of a pillar 80 mounted upon the automobile, a horizontal shaft rotatably mounted at the upper end of said pillar, a universally jointed shaft connected with said horizontal shaft, and adapted to be coupled with the propeller 85 of the aeroplane, a vertically disposed shaft passing through said pillar and geared to said horizontal shaft for driving the same from the automobile engine and means for vertically extending said pillar while maintaining 90 operative connection between said vertical and horizontal shafts.

3. In an apparatus for utilizing the power of the engine of an automobile for starting the engine of an aeroplane by swinging the 100 propeller, the combination of a telescopic pillar mounted upon the automobile, means for adjusting the telescopic sections of said pillar for varying the height thereof above the automobile, a horizontal shaft rotatably 105 mounted at the upper end of the upper section of said pillar, a universally jointed shaft connected with said horizontal shaft and adapted to be coupled with the propeller of the aeroplane, a vertically disposed 110 shaft; geared to said horizontal shaft for driving the same from the engine of the automobile and means whereby said vertically disposed shaft may be extended; simultaneously with the extension of said 115 telescopic pillar.

4. In an apparatus for utilizing the power of the engine of an automobile for starting the engine of an aeroplane, by swinging the propeller, the combination with a vertically 120 adjustable pillar mounted on the automobile, of a horizontally disposed shaft rotatably mounted in the upper end of said pillar, a universally jointed shaft connected with said horizontal shaft and adapted to be 125 coupled with the propeller of the aeroplane, a platform mounted on the automobile in position for the operator to attach the end of said universally jointed shaft to the propeller of the aeroplane and means for ad- 130

- justing the elevation of said platform above the automobile.
5. In an apparatus for utilizing the power of the engine of an automobile for starting the engine of an aeroplane by swinging the propeller, the combination with a telescopic pillar mounted upon the automobile, provided at its upper end with a substantially horizontally disposed universally jointed 5 starter-shaft, adapted to be coupled with the propeller of the aeroplane, of a platform for the operator to stand on when coupling said starter-shaft to the aeroplane propeller, means for adjustably varying the 10 elevation of said platform above the automobile and means adjustably connected with said platform for supporting the outer end of said universally jointed starter-shaft.
6. In an apparatus for utilizing the power of the engine of an automobile for starting the engine of an aeroplane, by swinging the propeller, the combination with a telescopic pillar mounted upon the automobile, provided at its upper end with a horizontal 15 shaft adapted to be driven by the engine of the automobile, said horizontal shaft being connected with a universally jointed shaft adapted to be coupled with the propeller of the aeroplane, of a second pillar mounted 20 upon the automobile, a frame adjustably mounted on said second pillar and provided with a platform upon which the operator 25 stands while connecting the end of said universally jointed starter-shaft with the propeller of the aeroplane, means for adjustably 30 clamping said platform at any desired elevation above the automobile, means for steadyng the outer end of said starter-shaft, comprising a pair of adjustable struts which cross one another X-wise, means for clamp- 35 ing said struts together at their crossing point and a bearing mounted thereon for supporting the outer end of said starter-shaft in the V-notch of said struts.
7. In an apparatus for utilizing the power of the engine of an automobile for starting the engine of an aeroplane by swinging the propeller, the combination with an upright pillar mounted on the automobile, of a substantially horizontally disposed starter- 40 shaft, mounted at the upper end of said pillar and adapted to be driven from the engine of the automobile, means whereby said shaft is adapted for horizontal and vertical movement, a sway-beam pivotally connected and 45 mounted for angular movement on the upper end of said pillar, one end of said sway-beam being connected to said starter-shaft to rotatably support the same and means connected with the other end of said sway- 50 beam for counter-balancing the weight of 55 said starter shaft.
- 60

GEOERGE SHAKESPEARE WILKINSON.
